LIFT TRUCK

Clifford Brooks Stevens, Milwaukee, Wis., and Clifford C. Bigley, Minneapolis, Minn., assignors, by mesne assignments, to Minneapolis-Moline, Inc., Hopkins, Minn., a corporation of Delaware

Filed Aug. 22, 1962, Ser. No. 71,409

Term of patent 14 years

(Cl. D14—3)

Fig. 1.

Fig. 2.

FIG. 1 is a side elevation of a lift truck showing our new design;

FIG. 2 is a top plan view of the lift truck of FIG. 1;

FIG. 3 is a front elevation of the lift truck of FIG. 1; and

FIG. 4 is a rear elevation of the lift truck of FIG. 1.

The essential features of the design reside in the portions shown in full lines on the drawings. The side not shown is substantially the same in appearance as the side shown in FIG. 1.

We claim:

The ornamental design for a lift truck, as shown and described.
